US00D826975S

(12) **United States Design Patent** (10) Patent No.: **US D826,975 S**
Baker et al. (45) Date of Patent: **** Aug. 28, 2018**

(54) **DISPLAY SCREEN OR PORTION THEREOF
WITH GRAPHICAL USER INTERFACE**

(71) Applicant: **Lutron Electronics Co., Inc.**,
Coopersburg, PA (US)

(72) Inventors: **Rhodes B. Baker**, Bethlehem, PA (US);
John H. Bull, Coplay, PA (US); **Erica**
L. Clymer, Northampton, PA (US);
Sanjeev Kumar, Harleysville, PA (US);
Jennifer Wong, Breinigsville, PA (US)

(73) Assignee: **Lutron Electronics Co., Inc.**,
Coopersburg, PA (US)

(**) Term: **15 Years**

(21) Appl. No.: **29/610,598**

(22) Filed: **Jul. 13, 2017**

Related U.S. Application Data

(63) Continuation of application No. 29/535,336, filed on
Aug. 5, 2015, now Pat. No. Des. 794,669.

(51) **LOC (11) Cl.** **14-04**

(52) **U.S. Cl.**

USPC **D14/487**

(58) **Field of Classification Search**

USPC D14/485-495

CPC G06F 3/0482

See application file for complete search history.

CLAIM

The ornamental design for a display screen or portion thereof
with graphical user interface, as shown and
described.

DESCRIPTION

The sole FIGURE shows a display screen or portion thereof
with graphical user interface showing our new design.
The broken lines illustrate a display screen or portion thereof
and form no part of the claimed design.

1 Claim, 1 Drawing Sheet
